UNITED STATES PATENT OFFICE.

WILLIAM JOHN BARBER, OF CLEVELAND, OHIO, ASSIGNOR TO THE LIBERTY MOP & SPECIALTY MANUFACTURING COMPANY, OF CLEVELAND, OHIO, A CORPORATION OF OHIO.

COMBINED MOP AND WRINGER.

1,249,885.

Specification of Letters Patent.

Patented Dec. 11, 1917.

Application filed February 19, 1917. Serial No. 149,452.

To all whom it may concern:

Be it known that WILLIAM JOHN BARBER, a citizen of the United States, residing at Cleveland, in the county of Cuyahoga and 5 State of Ohio, has invented certain new and useful Improvements in Combined Mops and Wringers, of which the following is a specification.

My invention relates to a combined mop 10 and wringer, which is of simple construction and more effectually and readily operated than the mop of my invention disclosed in Letters Patent No. 1,004,965, October 3, 1911.

15 In the accompanying drawing, Figure 1 is a perspective view of my improved wringer mop as it appears under the pressure of floor wiping operations, only a section of the handle being shown. Fig. 2 is a side view of 20 the same device folded as in wringing operations, and Fig. 3 is a front view of Fig. 2. Figs. 4 and 5 are perspective views of the link and holder plate, respectively.

The invention involves the use of a mop 25 of cloth or other pliable material suitable for the purpose, which is fastened to a handle 2' by a folding holder 3 and a crank 4, whereby the mop 2 may be stretched in flat wiping engagement with the floor upon inclining the handle and bringing pressure to 30 bear thereupon, and whereby the mop may also be wrung to remove the water after wiping operations by rotating the crank member 4 and rigidly setting the holder at substantially right angles to the handle, substantially as shown in Figs. 1 and 2 respectively. In my former device, these purposes were accomplished by utilizing a 35 slideable holder for the mop, but I find that a more effective action and durable construction is obtained by hinging the holder to 40 fold and unfold at two pivotal points in the connections. A simple and inexpensive arrangement of parts based on this concept 45 comprises a split ferrule member 5 fastened at the end of the handle or stick 2' by crimping its sides 6 upon the handle and riveting the ends together through ears 7 by a pivot pin 8, and also securing it in place by a tubular rivet 1', and the straight portion 9 of 50 the crank member 4 extends through this tubular rivet and the stick. A rotatable hand grip 10 serves to turn the crank, and a loop 11 forms part of the crank beneath the 55 handle and the cloth mop 2 is secured at one

end to this loop while the other end thereof is secured to a spreading eye 12 formed at the bottom or outer end of the wire holder 3 which is rigidly and immovably fastened upon a plate 14 pivotally suspended from 60 a link member 15 in hinged connection with pivot 8. Plate 14 is provided with clasp portions 16 bent around the straight parallel divisions 17 of the wire within the stop limits defined by the rounded shoulders 18 65 therein, and the sides of the plate are projected upwardly to one side of the plane of the plate to afford a set of ears 19 between which the side flanges of link member 15 are adapted to rest and be fastened by the pivot 70 and rivet pin 20. The upper or inner end 21 of holder 3 is also of spreading loop formation to afford a flat extended pressure medium adapted to flatten the mop and hold it to the floor in mopping operations, and 75 the intermediate divisions 22 of the wire holder are curved or spread laterally at each side of the median line to attain the same object. The pivot connection 20 is relatively near the inner end 21 of the wire 80 holder, and the length of the link member 15, or more definitely, the distance between the pivot pins 8 and 20, is proportioned to correspond to the extension inward of the loop end 21 so that when the parts are 85 folded to place the holder at right angles to the handle as shown in Fig. 2 that the end 21 will come inside of the handle and bear against the ears 7 of the ferrule member 5, thereby making a rigid right-angled 90 extension of the handle when pull is imposed upon the outer eye or loop 12 of wire holder 3 by twisting or wringing of the mop 2 upon rotating crank member 4. On the other hand, where the mop is in action upon 95 the floor, the link member 15 is adapted to fold and rest substantially flat upon the plate 14 with the pivot pin 8 forward of the pin 20 and nearer the middle of the holder 3 so that pressure upon the handle 100 may be applied more effectively upon the mop in wiping operations. In effect, a double hinge is provided for the mop frame which acts with perfect freedom but establishes positive working positions of the 105 parts for wiping and wringing operations of the mop.

What I claim is:

1. A handle having a ferrule member, a flanged link pivotally united with said fer-

- rule member, a plate having lateral projections pivotally united with said link, a wire holder affixed to said plate having an outer spreading end and a relatively shorter inner end adapted to bear against said ferrule in one folded position of the parts, a crank member upon said handle, and a mop connected with said crank member and the outer spreading end of said wire holder.
- 10 2. A handle having a flanged link member pivotally supported thereon and a flanged plate member pivotally secured to

the otherwise free end of said link member, a wire mop holder having spreading loops at its ends and clamped between its ends in said plate member, a crank rotatably mounted in said handle and having a looped end portion, and a mop secured to said looped portion at one end and to the outer loop of said holder at the other end.

15 Signed at Cleveland, in the county of Cuyahoga and State of Ohio, this 6th day of February, 1917.

20 WILLIAM JOHN BARBER.
